UNITED STATES PATENT OFFICE.

ARTHUR McDougall DUCKHAM, OF LONDON, ENGLAND.

GAS-FIRED POTTERY KILN.

1,423,408.

Specification of Letters Patent. Patented July 18, 1922.

Application filed December 29, 1921. Serial No. 525,723.

To all whom it may concern:

Be it known that I, ARTHUR McDougall DUCKHAM, a subject of the King of Great Britain, residing in London, England, have 5 invented certain new and useful Improvements in Gas-Fired Pottery Kilns (for which I have made application for patent in Great Britain, dated October 5, 1920, Serial No. 28,248), of which the following 10 is a specification.

In kilns for burning argillaceous ware such as bricks, pottery and the like, heat is generally supplied to the kiln at one or more points in the kiln chamber, the heat being 15 obtained by the direct combustion of solid fuel in grates forming part of the kiln chamber itself, or by the combustion of gases supplied by a central generator. In some cases hot air is supplied for completing 20 the combustion. The combustion zone is usually a small chamber of brickwork known as a bag, forming part of the construction of the kiln. The disadvantages of this system of heating are: (1) That the 25 brickwork of the kiln proper is subjected to the direct and intense heat of the combustion in the bag, with consequent heavy expenses for maintenance. (2) The bags being isolated in different parts of the kiln, 30 the heating is inclined to be localized about that portion of the kiln. (3) The heating usually being in a downward direction, the 35 materials are not consistently burnt throughout, the upper portions of the material in the kiln being more highly heated than the lower.

By this invention these disadvantages are overcome by providing one or more bags or 40 chambers for combustion independent of the kiln brickwork proper which divides the kiln into two or more parts and so that the heating gases escaping from the bag traverse the material contained in the kiln between the bag and the walls of the kiln, or 45 between the bags, the gases escaping through flues suitably formed by the stacking of the goods in a suitable manner. The bag is constructed of suitable brickwork and 50 preferably formed into separate chambers throughout its length. The gases for heating the kiln may be supplied to the bag by means of a flue or flues preferably situated beneath the bag and may enter the bag 55 through nostrils in its floor. Air for the combustion may be supplied through similar flues and nostrils, and combustion occurs

in the chamber or chambers of the bag. Dampers are provided for the proper regulation of the combustion. The top of the bag is preferably closed but ports may be 60 left in the top covering, in order that any desired amount of heat can be allowed to pass to the top of the kiln. The sides of the bag are conveniently formed of chequered brickwork, the openings in the sides 65 being so formed that they can be easily regulated between each charging of the kiln so as to give the desired intensity of heating in the different horizontal zones of the kiln. The material to be burned is placed in the 70 kiln, on each side of the central bag between it and the sides of the kiln, and, if desired, also above the top level of the bag. Since combustion occurs inside the bag and the latter does not form any part of the kiln, 75 the brickwork of the latter is not damaged in any way by the direct combustion of the gases. Further, the bag can be repaired or entirely renewed without disturbing the brickwork of the kiln proper. 80

Another advantage of this system of heating is that complete combustion may be obtained in the chambers of the bag itself, and in the gases passing through the comparatively small chequered openings; this means 85 that the gases passing forward to heat the material in the kiln will be even in temperature.

The heating gases on leaving the bag pass for the most part transversely through the 90 material in the kiln to the sides of the kiln, and may then pass downwards through ports in the floor, returning to the centre under the floor thus heating the latter, to the collecting flue through which they pass 95 to the chimney, to an adjoining kiln for the preliminary heating thereof or to any other device for using the heat still remaining in the gases.

In the accompanying drawings Fig. 1 is 100 a longitudinal vertical section and Fig. 2 is a transverse section on line 2—2 of Fig. 1 of a kiln constructed in accordance with the invention.

In the kiln *a* is built the gas bag *b* extending from end to end of the kiln along its middle. Heating gas from the producer *c* passes along the flue *d* and enters the gas bag through nostrils *e* in its floor. Air for combustion enters through inclined nostrils 110 *f*, one on each side of each gas nostril *e*, from flues *g* which extend in serpentine

form beneath the kiln between similarly serpentine flues *h* which convey products of combustion as presently explained.

The products of combustion escape from the gas bag through openings *i* in its sides and openings *k* in its cover *l*. Hence they travel transversely through the argillaceous material placed in the kiln chamber *m* and down the sides of the kiln, where passages have been left in piling up the material, into flues *n* which communicate by ports *o* with the aforesaid flues *h*. From the latter they pass to the chimney.

Having thus described the nature of the said invention and the best means I know of carrying the same into practical effect, I claim:—

1. A gas fired rectangular kiln for burning argillaceous ware, a gas bag therein constructed independently of the brickwork of the kiln proper, said gas bag dividing the kiln into a plurality of compartments, said bag having constricted apertures in the sides and top whereby heating gases escaping from the bag are evenly distributed and traverse the ware contained in the kiln between the bag and the walls of the kiln, the bulk of the gas passing through the ware in a horizontal direction.
2. A gas fired kiln for burning argillaceous ware having a gas bag constructed independently of the brickwork of the kiln itself and along the middle of the kiln, said gas bag being so formed that combustion of the gases takes place in the bag and is substantially complete before the heating gases leave the bag and whereby the products of combustion do not impinge directly on the brickwork of the kiln.
3. The construction of the gas bag referred to in claim 1, with a covered top and with constricted openings in its sides and top.
4. A gas fired kiln for burning pottery,

bricks or the like having a gas bag constructed independently of the brickwork of the kiln itself and along the middle of the kiln said gas bag being so formed that combustion of the gases takes place in the bag and is substantially complete before the heating gases leave the bag and that the products of combustion do not impinge directly on the brickwork of the kiln, and a covered top with constricted openings in its sides and top.

5. A gas fired kiln for argillaceous ware comprising within the kiln structure, a gas bag sub-dividing the kiln chamber externally to the said gas bag into compartments and constructed independently of the brickwork of the kiln itself, and flue openings in the floor of the kiln chamber adjacent to the sides thereof, for the purpose set forth.

6. A gas fired kiln for burning argillaceous ware comprising within the kiln chamber, a gas bag constructed independently of the brickwork of the kiln itself and extending along the middle line of the kiln chamber and from end to end thereof, and flue openings in the floor of the kiln chamber adjacent to the sides thereof, for the purpose set forth.

7. A gas fired kiln for burning argillaceous ware, comprising within the kiln chamber, a gas bag constructed independently of the brickwork of the kiln itself and extending along the middle line of the kiln chamber and from end to end thereof, a cover to the top of the said gas bag, openings in the said cover and in the sides of the bag, the said openings being adapted to be varied by insertion or removal of bricks and flue openings in the floor of the kiln chamber adjacent to the sides thereof, for the purpose set forth.

In testimony whereof I have signed my name to this specification.

ARTHUR McDougall DUCKHAM.
